UNITED STATES PATENT OFFICE.

LEO F. PERRIN, OF PORT HURON, MICHIGAN.

SANITARY COVER FOR RECEPTACLES.

1,185,710.

Specification of Letters Patent. Patented June 6, 1916.

Application filed April 26, 1915. Serial No. 24,060.

To all whom it may concern:

Be it known that I, LEO F. PERRIN, a citizen of the United States of America, residing at Port Huron, in the county of St. 5 Clair and State of Michigan, have invented certain new and useful Improvements in Sanitary Covers for Receptacles; and I do hereby declare the following to be a full, clear, and exact description of the invention, such as will enable others skilled in the art to which it appertains to make and use the same.

This invention relates to sanitary covers for receptacles.

15 It is an object and purpose of the invention to provide a cover adapted to be attached to tubs, pails, barrels or the like and especially to ice-cream receptacles and tubs containing butter.

20 A further object of the invention is to provide a sanitary cover with means by which it can be secured to any desired receptacle such that when in place, the contents of the receptacle is practically sealed 25 against removal by one not authorized, whereby said contents cannot be disturbed before it reaches its destination.

The construction by which these ends are attained, together with others not specifically enumerated is shown in the accompanying drawing, in which;

30 Figure 1 is a front elevation of a receptacle having my improved cover thereon in closing position. Fig. 2 is a view from the rear of Fig. 1. Fig. 3 is a plan view of the cover. Fig. 4 shows a vertical section, somewhat reduced in size, with the cover removed from the receptacle. Fig. 5 is a horizontal section taken through the front of the cover 35 and illustrating its method of attachment to the receptacle at this point. Figs. 6 and 7 show in front elevation and section a securing eye formed in the cover; and Fig. 8 is an elevation of the eyes formed at each 40 side of the cover for attachment thereof to the handles of the receptacle.

Like reference characters refer to like parts throughout the several views of the drawing.

45 The receptacle to which the cover is to be applied is indicated at 1. The cover may be formed from canvas or other suitable material which may be treated with any suitable water proof compound whereby it may 50 be readily washed and cleaned and kept in sanitary condition. This cover top 2 is cir-

cular in outline and has depending sides 3 which are divided at the front to form two flaps 4 and 5 as shown, the flap 5 overlapping flap 4. Adjacent the edge of flap 4 an 60 elongated eye 6 is provided in the flap while flap 5 is similarly provided with an elongated eye 7 both eyes 6 and 7 being of substantially the formation shown in Figs. 5, 6 and 7. At either side of the cover, eyes 65 8 are also secured near the lower edges of the sides 3.

At its rear side substantially opposite the dividing line between flaps 4 and 5, the cover is cut diagonally and a portion lapped 70 over the adjacent portion as shown at 9 in Fig. 2. The overlapping portions are fastened together and at the same time a loop 10 of metal is secured to the depending sides of the cover, suitable rivets passing 75 through the loop and through the overlapped portions of the sides 3 of the cover. This construction makes the diameter at the lower edges of sides 3 less than it is where said sides join the top 2, so that when applied to a receptacle the lower edges bind 80 tightly against the receptacle as will be readily understood. The member 10 is pivotally connected to the receptacle by means of a nail 11 driven through and clenched on 85 the inner side of the receptacle whereby the cover is permanently secured to the receptacle.

A receptacle provided with a cover and attached thereto in the manner thus described 90 may be closed readily, the eye 6 of flap 4 being first passed over a device 12 which is permanently secured to the receptacle at a point diametrically opposite the member 10. Member 12 is formed with an enlarged head 95 13, as shown, adapted to pass through the eyes 6 and 7. After the flap 4 has been connected with the member 12 flap 5 is connected by forcing its eye 7 over the enlarged head 13. It will be apparent that by reason 100 of the rounded outer portion of the head 13 the eye 7 as it is forced over this head serves to draw the lower edge of the sides 3 of the cover tightly against the receptacle and the head is so positioned that when both flaps 105 are connected thereto the eye 7 bears against one side of the head at its widest portion. The flaps may now be retained in position by passing a wire 14 through the head 13 and sealing it in any well known manner. This 110 will serve to connect the cover to the receptacle at the front and rear and to further

secure it at the sides wires 15 may be passed through the eyes 8 and the handles 16 positioned at diametrically opposed points on the receptacle, these wires being also sealed 5 the same as wire 14.

A receptacle cover of this construction when applied serves to render access to the receptacle by persons not authorized practically impossible, and entirely impossible without 10 notice, from breaking the seals, to those to whom the receptacle is sent. By means of this construction the closure may be drawn very tightly against the outer side of the receptacle precluding the entrance of any foreign matter to the interior, and after use, if 15 the closure at any time becomes soiled or otherwise rendered unsanitary, it may be readily cleaned before use again.

I claim:—

20 1. A cover for receptacles comprising a top having the formation of the top of the receptacle to be covered, sides depending from the outer edges of the top, said sides at one point being divided and formed with 25 flaps one overlapping the other, eyes in the flaps adapted to be positioned one over the other, a loop connected to the sides at a point substantially opposite the eyes in the flaps, and eyes, one at each side between the loop 30 and flaps, positioned in the depending sides of the cover, substantially as described.

2. A cover for receptacles comprising a top having the formation of the top of the receptacle to be covered, sides depending from the outer edges of the top, said sides 35 at one point being divided and formed with overlapping flaps, elongated eyes formed in the flaps, a metal loop connected to said sides at a point substantially opposite the eyes in the flaps, and additional eyes positioned in the depending sides at either side of the cover between the eyes in the flaps and the loop, substantially as described. 40

3. In combination, a receptacle, handles on the receptacle, a member having a rounded head secured to the receptacle between the handles, a cover provided with depending sides, a loop attached to the cover and to the receptacle, overlapping flaps each having an eye therein passing over the said member 45 on the receptacle, eyes in the cover adjacent the handles on the receptacle, means securing the cover to the handles through the eyes and means to retain the flaps in position over the head of the said member, substantially 50 as described.

In testimony whereof I affix my signature in presence of two witnesses.

LEO F. PERRIN.
